MILTON ALDEN, OF SPRINGFIELD, MASSACHUSETTS, ASSIGNOR TO THE ALDEN MANUFACTURING COMPANY, OF BROCKTON, MASSACHUSETTS, A CORPORATION OF MASSACHUSETTS

ELECTROMAGNETIC PICK-UP

Application filed January 17, 1927. Serial No. 161,620.

The main object of my invention is to produce a device for the conversion of the mechanical movement of a needle or stylus caused by the undulations of the grooves of a sound record into electrical pulsations of corresponding frequency and amplitude—such devices are frequently called "magnetic pick-ups."

Another object is to provide a device of the above description in which the moving parts are light and therefore of little inertia and hence readily able to accurately follow the undulations of the record.

Another object is to produce a device as above described having a short air-gap, hence a large percentage change of magnetic circuit reluctance and therefore of high sensitivity.

Another object is to produce a magnetic pick-up which will operate on the type of record which produces movement in a plane transverse to the axis of the stylus or on a record which produces movement along said axis by merely rotating the reproducer into one of two positions.

Referring to the drawings:

Fig. 1 is a central vertical partly sectional view of one embodiment of my invention.

Fig. 2 is a partly sectional view of part 30 of another embodiment.

Fig. 3 is a central vertical partly sectional view of still another embodiment.

In Fig. 1 the pole pieces 5 and 6 are secured in some convenient manner to the ends 25 of the permanent magnet 7. On these pole pieces are mounted the bobbins or spools 8 and 9 which carry the windings 10 and 11 which may be connected to the input of a suitable amplifier (not shown). The armature 12 is held against the pole tip 13 by means of the resilient washer 14 which is pressed upon by the bar or strip 15. This strip 15 is provided with an aperture 16 of sufficient size to afford adequate clearance for the stylus holder 17. The stylus holder 17 is secured to the armature 12 at a point such as 18 close to the point of contact with the pole tip 13. The position of the bar 15 is regulated by the thumb screws 19 and 20 which operate in the threaded bushings studs 21 and

22. It will be seen that adjustment of the nut 20 will produce a large change in the air gap 23 between the armature 12 and the pole tip 24, while by adjusting both nuts the air gap can be left unchanged and the compression of the resilient washer 14 may be varied, thus affecting the damping of the armature or reed 12. It will be seen that the lateral motion of the stylus 25 will change the air gap 23, thus changing the magnetic circuit consisting of the permanent magnet 7, the pole piece 6, the armature 12, the air gap 23 and the pole piece 5, thus producing voltages, substantially proportionate to this movement, in the windings 10 and 11 which may be amplified and reproduced in any suitable manner.

With the more usual type of lateral cut record in which the music is recorded by radial changes of the needle path along the record, the section shown in Fig. 1 would be along the plane passing through the radii of the record, but if the reproducer is rotated through 90 degrees so that the section shown is in a plane normal to a radii of the record, the "hill and dale" type of record will produce the desired movement of the armature.

In Fig. 2 the armature 12 is secured in any suitable manner directly to the pole piece 13 as by the screw 13'. Two resilient damping blocks 30 and 31 are placed on either side of the armature and are held between the armature and the spool head 32 and between the armature and the clamping bar 33, respectively. The knurled nut 34 is then used to regulate the size of the air gap 23. The magnetic system of the embodiment shown in Fig. 2 is similar to that of Fig. 1 and Fig. 3.

In Fig. 3 the stylus holder 17 carries a collar 40 which is preferably made integral. This collar is supported by two yielding or resilient washers 41 and 42. The washer 41 is positioned on the adjusting bar 43 by the externally threaded ring 44. The cup 45 whose interior threads engage the threads of the ring 44 serves to clamp the washer 42 against the collar 40 of the stylus 17. The cup 45 is provided with an aperture 46 of sufficient size to allow adequate freedom of movement of the stylus holder 17. By rotat-

ing the cup 45 the clamping action of the two resilient washers 41 and 42 upon the collar 40 may be varied, thus varying the damping action upon the moving parts. The relative clearance between the pole pieces 13 and 24 and the armature 12 may also be regulated by the rotation of the knurled headed screws 47 and 48.

In all three embodiments shown the stylus 10 25 is secured in the stylus holder 17 by the thumb screw 49.

It has been found that the structures described are highly efficient needing less amplification for a given output volume than 15 is usually considered necessary. By using but one air gap and having that adjustable so that it can be made smaller than would be manufacturingly practicable if made fixed, a large change of magnetic reluctance with extremely small movement is secured, which I believe accounts for the high sensitivity.

The simplicity and lightness of the moving parts, combined with the fact that these parts are yieldingly held in position, produces extremely faithful reproduction and the natural period and harmonics of the armature do not cause the corresponding frequencies to be emphasized as often occurs in other devices of this nature.

30 It is also possible by varying both the air gap and the yieldingly compressive force, which holds the armature in position, to change the characteristic of the device sufficiently to make it adjustable for a wide range 35 of amplifiers, or other varying conditions.

It is not unusual in devices of this nature for the air gap to become clogged with fillings, dust or other foreign material. With my construction the armature may be readily removed and such material wiped from the armature and pole-tip. It is also extremely easy to replace the armature and stylus holder in case it becomes bent, crystallized or otherwise injured.

45 Another novel feature of my device is that the adjustment of the air gap and damping may be effected by means of the screws such as 19, 20, 47 and 48 while a record is being played and can thus be adjusted with little 50 difficulty to maximum sensitivity or to suit the personal preferences of the user as to quality.

I claim:

55 1. A double pole magnet having an armature pivotally supported by one of said poles normally out of engagement with the other pole and a stylus directly attached to the armature near its pivoted end and between the two poles.

60 2. In a magnetic pick-up a bi-polar magnetic system and having an armature in contact with one pole, a stylus carried by said armature, a damping member adjacent to said 65 stylus, and common means for adjusting the

damping member and the air gap, said means acting directly on said damping member.

3. A magnetic pick-up device comprising a magnet having pole pieces projecting from one side, an armature pivoted below one pole piece, a stylus carried by the armature, a damping means for said armature, and a screw having an adjusting end accessible above the magnet for adjusting the armature so as to permit change of the air gap and also simultaneous change of the damping effect while the device is in operation.

4. A double pole magnetic system comprising a permanent magnet, two pole pieces carried by said magnet, one of said pole pieces carrying a winding, an armature pivotally supported by one of said poles normally out of engagement with the other pole, one of said pole pieces, said armature having a stylus holder rigidly attached to said armature at a point on said armature between said pole pieces and at right angles to said armature.

5. A magnetic pick up having a magnetic system consisting of a permanent magnet having two pole-pieces carrying windings, an armature pivotally supported by one of said poles normally out of engagement with the other pole, and a stylus directly attached to and disposed at right angles to said armature and between said pole pieces so as to vary the reluctance of said magnetic system substantially in accordance with the variations of a sound record, said armature being yieldingly supported against said contacting pole-piece.

6. A magnetic pick-up having a magnetic system consisting of a permanent magnet having two pole pieces carrying windings, an armature pivotally supported by one of said poles normally out of engagement with the other pole, and a stylus directly attached to and disposed at right angles to said armature so as to vary the reluctance of said magnetic system substantially in accordance with the variations of a sound record, said armature being yieldingly supported against said contacting pole-piece, and adaptable by a 90° rotation of said pick-up to function either with the type of sound record whose variations are radial or with the type of sound record whose variations are parallel to its axis of rotation.

MILTON ALDEN.
